US0D1076831S

(12) **United States Design Patent** (10) **Patent No.:** **US D1,076,831 S**
(45) **Date of Patent:** **** May 27, 2025**

(54) **INPUT DEVICE**

(71) Applicant: **Leica Biosystems Imaging, Inc.**, Vista, CA (US)

(72) Inventors: **Yunlu Zou**, Vista, CA (US); **Andrew Garvey**, Vista, CA (US); **Philip Nguyen**, Vista, CA (US)

(73) Assignee: **Leica Biosystems Imaging, Inc.**, Vista, CA (US)

(**) Term: **15 Years**

(21) Appl. No.: **29/918,936**

(22) Filed: **Nov. 30, 2023**

(51) **LOC (15) Cl.** **13-03**

(52) **U.S. Cl.**

(57) **CLAIM**

The ornamental design for an input device as shown and described.

DESCRIPTION

FIG. 1 is a top perspective view of an input device, showing my/our new design;

FIG. 2 is a rear perspective view thereof;

FIG. 3 is a front elevational view thereof;

FIG. 4 is a back elevational view thereof;

FIG. 5 is a left elevational view thereof;

FIG. 6 is a right elevational view thereof;

FIG. 7 is a top plan view thereof; and,

FIG. 8 is a bottom plan view thereof.

The even spaced broken lines in the drawings depict portion of the input device that form no part of the claimed design. The dash-dot-dash broken lines define the bounds of the claimed design and form no part thereof.

1 Claim, 7 Drawing Sheets
